UNITED STATES PATENT OFFICE

2,513,635

WATCH STEM TRIMMING APPARATUS

Walter E. Frisk, Chicago, Ill., assignor to Montgomery Ward & Co., Incorporated, Chicago, Ill., a corporation of Illinois

Application June 27, 1946, Serial No. 679,816

5 Claims. (Cl. 51—98)

1

The present invention relates to an apparatus for accurately adjusting the length of watch stems and for threading the winding and setting wheel or crown thereonto. The machine is particularly designed so as to be operated by relatively unskilled operatives, being provided with such means as to enable extreme accuracy and uniformity in trimming to be attained with a minimum of effort, and with the greatest possible speed compatible with accuracy.

Watches are usually made on a large scale by manufacturers of watch-works which are sold to the manufacturers of the completed watches, who frequently either make their cases or buy them from watch-case manufacturers. The manufacturers of the works usually provide the watches with winding and setting stems which are of a greater length than is desired in the ultimate watch, this being done in order to enable the necessary adjustment to be made by the actual producers of the finished watch. There must be the proper spacing of the winding wheel or crown on the stem so as to allow the proper clearance between the crown and case, and also to allow for two different positions, one with the stem pushed all the way in for winding the watch, and another with the stem partly pulled out, in order to set the watch. Proper and uniform spacing is also desirable from an appearance standpoint.

The winding and setting wheel or crown is usually attached to the stem by being threaded thereon. It is necessary that the crown be rather firmly screwed onto the threads at the end of the stem so that it will not readily become unscrewed when setting the hands either ahead or back.

Most watches are so made that a clockwise movement of the stem will wind the watch, while on the return movement a pawl and ratchet within the watch allows the stem to be turned counter-clockwise without imparting any movement to the internal portions of the works of the watch. In setting, however, it is often desirable that the hands be moved either forward or back. If the crown or winding wheel were not firmly screwed upon the threads on the stem, then it would be prone to become unscrewed and possibly dropped or lost.

It has formerly been the practice of watch assemblers to take the works as received from the works manufacturer, remove the stem from the works, unscrew the crown, and then by means of a nipper and a file, emery wheel, or other abrasive implement, to abrade the end of the stem

2

until it has exactly the desired length, whereafter the crown was screwed back on to the thus shortened stem. Self evidently, this required great care which, particularly in the case of small wrist watches, such as ladies' watches, necessitated the use of a magnifying glass or other ocular aid, and was very trying work.

Under modern conditions of mass production such slow work is of course intolerable, as it adds too much to the cost of the watch.

Accordingly, it is one of the objects of the present invention to provide a machine which can be manipulated by relatively inexperienced operators, but which will nevertheless, with a great degree of accuracy, shorten watch stems so that they will accurately fit any particular selected case.

A further object of the invention is to provide a machine which will receive a watch works, and whereby, with great facility and accuracy, the winding and setting wheel or crown may be unscrewed from the stem thereof and stored temporarily, the stem trimmed or ground off to the exact length desired, and the crown then screwed back on the stem to an exact predetermined position.

Other objects of the invention will become apparent from a further description of the apparatus involved which is illustrated in a plurality of sheets of drawings, in which:

Fig. 1 is a top plan view of the apparatus of the present invention;

Fig. 2 is a perspective view from above and to one side looking at what amounts to the left hand side of the machine when in use;

Fig. 3 is a perspective view of the machine viewed from the lower right hand corner thereof, showing the position of the parts of the machine when the latter is performing the stem-trimming operation;

Fig. 4 is a top plan view of a portion of the machine showing the position of the parts just immediately prior to the trimming of the stem;

Fig. 5 is a section along the line 5—5 of Fig. 6;

Fig. 6 is a section along the line 6—6 of Fig. 1 with some of the parts broken away to expose underlying details, and

Fig. 7 is an elevational view of a portion of the machine, showing particularly the means for actuating the motor illustrated in Figs. 1, 2 and 3.

The machine comprises a suitable base upon which are mounted a number of interacting instrumentalities which may be broadly designated as a travelling carriage for holding the watch works to be acted upon. Said carriage is pro-

vided with vise-means for strongly and firmly embracing the stem of the watch at a point very close to the works, so as to hold it rigid and prevent its rotation in either direction. The carriage is slideable on said base between lateral guides which assure its accurate travel back and forth, the travel of the carriage also being limited by certain adjusting screws fastened to the base. Cooperating with the carriage are means for embracing and unscrewing the winding and setting wheel or crown, and for holding the same during the stem-cutting operation. The latter operation is performed by a motor-driven abrasive element.

The motor and its abrasive element are accurately adjustable relative to the other portions of the apparatus, so as to insure the cutting off of exactly the right amount of the protruding watch stem. The abrasive wheel, moreover, is surrounded by a stationary housing provided with a suitable slot for the entry and exit of the watch stem which is to be trimmed, the said housing also having a small exhaust fan and exhaust tube through which metallic particles which are ground off the end of the watch stem are blown to a suitable point remote from the apparatus so as to preclude the possibility of small metallic particles getting into the works which are on the carriage.

The device, moreover, is also provided with a temporary cover so as to keep dirt and other material from getting into the works during the operation.

The base is also provided with a microswitch which is in series with the main switch of the motor and which is so oriented that the motor will not be actuated whenever the carriage has made contact to close the microswitch, and which will shut the motor off as soon as the carriage has carried the work out of operative relation with the abrasive element.

In describing the exact details of the apparatus in connection with the drawings, it is to be understood that this description is purely for purposes of exemplifying the broad principles of the invention, which is not limited to the precise constructional details shown, but rather is to be construed in the light of the hereunto appended claims.

The device in its broader aspects can best be understood by a perusal of Figs. 1, 2 and 3.

Thus, upon a suitable, preferably heavy metallic base plate 10, there are mounted two exactly parallel metallic guide rails 11 and 12, which are fastened to the base plate 10 by a plurality of countersunk screws 13. Slidable within the space provided by the parallel rails 11 and 12 is a heavy metallic mounting carriage 14 which is provided at its upper side with a watch-mounting or holding platform 15 which lies partly within a suitable depression 16, and which platform is capable of accurate adjustment in a vertical position by being made integral with or attached to a suitable screw 17 which is threaded into a suitable threaded opening 18 within the mounting block or carriage 14. The edge of the platform 15, which is circular, is knurled so that it may be manually rotated and thus adjusted vertically so as accurately to determine the position of the watch relative to the base 10, that is to say, the distance from the base to the stem of the watch. After this distance has been properly determined, the screw 17 can be kept from movement by means of the locking screw 19 which is provided with the knurled operating wheel 20. The watch

moreover is kept from lateral movement by lying partly within a suitably shaped depression 21 within a plate 22 which is attached to the top of the carriage 14 by means of screws 23. The watch works which are usually supplied by the manufacturer in a cheap metallic half-housing 24, is placed within the opening 21, thus lying directly upon the aforementioned adjustable platform 15. The stem 25 of the watch extends beyond the inside vertical surface of the mounting carriage 14 between jaws 26 and 27 of a suitable vise, one jaw 27 of which is permanently affixed to the carriage 14 by means of screws 28 and 29. The other jaw 26 of the vise is pivotally mounted on the carriage 14 by means of the screw 30 which acts as a fulcrum about which the jaw may move.

The jaws 26 and 27 of the vise, which are sharpened down at their adjacent ends to narrow edges, are further provided with semicircular notches 31 and 32 (Fig. 5), respectively, which are of such a dimension that when the vise is in the closed position, the watch stem will be firmly held against movement in the circular opening provided by the meeting of the semicircular openings 31 and 32. The jaw 26 of the vise is moreover urged into open position by means of a tension spring 33, one end of which is affixed to a pin 34 which is secured to and which projects from the carriage 14, while the other end of the spring is attached to a suitable pin 35 carried by the outer end of said jaw.

The means for elevating the outer end of jaw 26 so as to close the vise, consist of a suitable cam 36 which is actuated by means of a shaft 37, which traverses carriage 14 and to which is attached a suitable handle 38. By a rotational movement of the shaft 37 and the thereto connected cam 36, the outer end of jaw 26 may be raised or lowered so as to cause said jaw either to engage or disengage the watch stem 25. Suitable stops 39 are provided on the shaft 37 as for example by extending from an enlarged collar 40 thereon, the stops 39 being limited in their movement by abutting against a suitable abutment 41.

A cover 42, swingable upon a hinge 43 and provided with a handle 44, is provided for temporarily covering the watch works 45 during the operation. The extent of travel of the carriage 14 in either direction is controlled by means of the stop screws 47 and 48 at the opposite ends of the base 10, said screws being provided with lock nuts 47' and 48' respectively, the screws being threaded into posts 49 and 50 respectively on the base plate.

Means, broadly designated by the reference numeral 51, are provided for unscrewing, and holding the winding wheel or crown 52 (see Figs. 1 and 6), these means consisting of a post 53 upon which there is pivotally mounted at 54 a tubular member 53' in which is slidably mounted a rod 54 which may be locked in position by screw 54'. Suitably fixed to rod 54 is a transversely disposed sleeve 55 in which there is slidably movable a crown-clamping chuck 56, the internal construction generally of which can best be seen from the partial sectional showing in Fig. 6. This device consists of a plurality of clamping fingers 57 which are capable of being radially spread apart under the influence of a push-rod 58 which is provided with a knurled operating knob 59, the rod 58 being threaded into the interior of a tube 60, so that the amount of space between the fingers 57 can be controlled. This

type of chuck wrench is well known and is widely used in the machine industry, for unscrewing and screwing small nuts and bolts and in effect is a sort of automatic clamping wrench. In any event, this chuck wrench is slidable in the sleeve 55 and is so constructed that the device may be caused to spread its fingers 57 as to embrace the outer knurled edge of the crown 52, whereafter, with the stem being held by the vise jaws 26 and 27, the crown can be unscrewed from the stem 25 by a counter-clockwise movement of the chuck wrench until it has been completely disengaged from the stem 25. The end of the chuck wrench is then partly withdrawn into the sleeve 55 so as to keep the crown in readiness for re-attachment after the further operations about to be described.

The crown having been removed, the member 53' is swung back about its pivot 61 and laid down upon a suitable resilient stop 62 as seen in Fig. 3. Thereafter the carriage, with the watch thereon and with the stem 25 extending therefrom, is ready for the next operation, which is performed by the trimming instrumentality, which latter is constituted as follows:

A suitable sub-base 65 is mounted upon and rigidly secured to the base 10, and mounted for slidable adjustment thereon is a platform 66, the position of which can be accurately adjusted by means of a handle 67 operatively connected to said platform and said sub-base 65, so that by rotating said handle the platform may be slidably adjusted. Suitable markings 70 which are graduated so as to indicate the extent of travel of the platform 66 relative to the base 65 are provided so that, for example, each division will correspond to a longitudinal movement of the platform of one one-thousandth of an inch.

Mounted on and rigidly secured to the platform 66 is a suitable electric motor 71 provided with an electric cable 72 which is connected with a suitable source of electric current. The motor has attached to it, for example by means of the chuck 73, a small longitudinally extending shaft 74 upon the end of which is mounted, in the order named, (Fig. 4), a small fan 75 having a plurality of blades 76, and an abrasive wheel 77. Surrounding the fan 75 and the abrasive wheel 77 is a housing 80 which does not partake of the movement of the motor and shaft but which is held in proper alignment therewith by means of the standard 81 which is secured by means of the screws 82 to the base 10. The casing 80 moreover has an outlet nipple 84 to which may be attached a suitable tube 85, through which particles abraded from the stem 25 may be discharged to a suitable point remote from the apparatus. The housing 80 is provided with an anterior substantially circular closure 86 which is provided with a radial slot 87 through which the watch stem 25 may freely pass. The said closure 86 is moreover secured to the housing 80 by means of the screw 88 about which it is swingable so that the interior of the housing 80 may be made accessible for the purpose of replacing the grinding wheel or disc 77.

The carriage 14, when it is slid to the left (in Figs. 1, 2 and 4) or to the right (as shown in Fig. 3), serves to actuate a suitable electric switch 90 which lies within a suitable opening 91 cut in the base 10, the said switch however having a small actuating button 92 which protrudes very slightly above the upper plane of the base 10 so that the carriage 14, when slid to the left (relatively as shown in Fig. 4), and as best seen

by Fig. 7, will serve to depress the button 92 to close the switch, and thereby to actuate the motor. The motor, however, is also provided with a separate control switch 93, which can best be seen in Fig. 3, and which serves entirely to cut off the motor when it is not in use. Ordinarily, however, the main control switch 93 is in the "on" position.

Whenever the carriage 14 with the watch works 45 thereon is slid into the position shown in Fig. 3, the motor will be in operation and hence the grinding wheel 77 will be spinning. The watch stem 25 will thus be brought into engagement with the wheel 77 which will cut and abrade it 15 down so that its end will be in absolute contact with the abrasive side of said wheel. Inasmuch as the position of this wheel relative to the carriage 14 can be very accurately determined by means of the adjusting handle 67, the amount 20 which is cut from the stem 25 may be consequently very accurately controlled, the entire operation requiring only about a second or so. Once this has been accomplished, the carriage is moved back to its first initial position, that is, to the 25 left, as seen in Fig. 2 and Fig. 3, and to the right as shown in Fig. 1, until the carriage 14 again abuts against the end of the stop screw 47, thereby again bringing the watch stem into its original position relative to the base. Thereafter the 30 crown 52, which in the meantime has reposed within the jaws of the chuck wrench 56, is ready to be screwed back on to the now shortened stem.

However, in order to prevent the crown 52 from being screwed too far on to the stem 25, there is 35 provided a gauge 100 (best seen in Fig. 5) which has a bifurcated end 101. This gauge 100 is rotatable about the pivot 102 being urged into an upright position by means of a spring 103. However, the gauge can be manually swung so 40 that it will embrace the stem 25 between the two bifurcations of the end 101, being held in place by the finger of the operator, whereafter the crown 52, which is still being held by the jaws of the chuck wrench 56, is screwed back by a clockwise movement on to the end of the stem 25, the extent to which it can be so screwed, however, being limited by its contact with the end 101 of the gauge 100. Said gauge thus serves as a means 45 of properly spacing the crown with respect to the watch casing, so that the position of all of the crowns of the watches operated upon will be uniform. As soon as the crown is tight, a proper pushing movement on the end of the chuck wrench will cause the latter to disengage the 50 crown, whereafter the wrench is pulled back and the gauge 100 is allowed to snap back into vertical position. The watch works may then be removed by opening the vise jaws 26 and 27, swinging back the cover 44, and lifting the works from the machine, 55 whereafter a new one is substituted, and the entire operation is repeated.

In order further to assure the proper axial alignment of the crown and the chuck wrench 56, there is provided a stop 104 which is carried 60 by the carriage 14 and against which, when the latter is in its original or starting position, the side of the chuck wrench carrier tube 53 abuts (see Figs. 1 and 6).

It is believed that from the above description 65 the operation of the device is substantially self evident, but may be recapitulated for sake of preciseness as follows:

The watch works, having been placed upon the already described platform 15, the cover 42 is 70 swung to position to enclose the same, where- 75

after the protruding stem 25 is grasped and locked between the two vise jaws 26 and 27. Thereafter, by means of the chuck wrench 56, the crown is unscrewed from the stem 25. The carriage, with the watch mounted thereon, is then moved to the extreme opposite position so as to cause the stem to be cut off by the accurately adjusted grinding wheel 71. The carriage is then returned to the original position, the spacing gauge 101 swung into operative position, and the crown screwed back on to the stem, whereafter the gauge is swung back into a vertical position, the vise jaws 26 and 27 released, and the works removed from the carriage.

It is of course obvious that the exact means for actuating the movable portions of the vise is subject to considerable mechanical equivalents. Moreover, the means for unscrewing the wheel may be omitted as the wheel could be conceivably unscrewed by hand and laid upon the base, and then put on again by hand, which, however, is a rather awkward and time consuming operation, particularly with very small watches.

The various steps provided to limit the movement of the carriage may, of course, take different forms, and the means for adjusting the grinding wheel may be different than those shown, provided only that its accurate adjustment relative to the watch stem can be accomplished. If desired, and mainly in order to keep the slideway between the rails 11 and 12 clean, the carriage 14 may be provided with suitable felt strips 110 which are secured to the carriage 14 by means of holding strips 111 secured to the carriage by screws 112. This will prevent dirt or metallic particles from falling into the slideway and possibly interfering with the free movement of the carriage or with the operation of the switch button 92.

Saving for himself the use of such equivalents as will readily occur to those who are skilled in the art into which the present invention falls, applicant claims:

1. Apparatus for diminishing the length of a crowned watch-works stem which comprises a rigid base, a reciprocatory carriage, vertically adjustable watch-works-supporting means on said carriage, vise-means secured to said carriage for engaging a watch-works stem and preventing its rotation, stops limiting the reciprocatory travel of said carriage in a motor-base secured to said rigid base, a motor-support adjustably

mounted on said motor-base, a motor rigidly mounted on said support, an abrasive wheel mounted on the shaft of said motor in a position to intercept said watch-works stem when supported on said carriage, and means associated with said wheel for removing cuttings to a point of disposal.

2. The apparatus as claimed in claim 1, when provided with an electrical switch for operating the motor, said switch being in the path of said carriage and actuated by contact therewith.

3. In an apparatus for trimming crowned watch-works stems, the combination of means for supporting the works in a predetermined position, means for clamping the stem thereof against rotation, means for unscrewing the crown from said stem, means for diminishing the length of the stem, gauge means capable of partly surrounding said stem, and means for re-screwing the crown onto the stem, the extent of said re-screwing being limited by said gauge means.

4. In an apparatus for trimming crowned watch-works stems, the combination of a watch-works-supporting carriage, and a stem-engaging gauge limiting the extent to which a crown can be threaded onto the stem of a watch-works supported on said carriage; said gauge being movably mounted on said carriage so as to permit of movement into and out of operative position.

5. The combination as claimed in claim 4, in which the gauge is spring-biased into inoperative position.
